PRESSURE ATTACHMENT FOR GARMENT-PRESSES.

1,386,665.

Specification of Letters Patent. Patented Aug. 9, 1921.

Application filed March 12, 1917, Serial No. 154,195. Renewed December 28, 1920. Serial No. 433,738.

To all whom it may concern:

Be it known that we, CHARLES E. WAREAM and CHARLES L. BRALEY, citizens of the United States, residing at Cincinnati, 5 in the county of Hamilton and State of Ohio, have invented certain new and useful Improvements in Pressure Attachments for Garment-Presses, of which the following is a specification.

10 This invention relates to garment presses and particularly to power attachments therefor.

More specifically the invention relates to 15 a garment press provided with manually operable means for closing it and power mechanism preferably of the pneumatic type for exerting a final increased pressure upon the pressing members for performing the final pressing operation.

20 The invention may be further briefly summarized as consisting in the construction and combination of parts hereinafter set forth in the following description, drawing and claims.

25 Referring to the drawings Figure 1 is a side elevation of a machine with the final pressure mechanism applied thereto; Fig. 2 is a view showing the valve mechanism with the exhaust valve shown in section on 30 the line 2 in Fig. 3; Fig. 3 is a sectional view on the line 3-3 of Fig. 2; Fig. 4 is an enlarged view of a portion of the machine with the parts in the positions they assume when the press is closed; Fig. 5 is a front 35 view of the lower treadle with the parts in the same position shown in Fig. 4; Fig. 6 is a horizontal sectional view on the line 6-6 of Fig. 4; Fig. 7 is a top plan of the final pressure mechanism removed from the 40 machine, and Fig. 8 is a perspective view of the pressure head.

In the arrangement shown in the drawings the main frame comprises a base 1, a forwardly extending buck support 2 and an 45 upwardly extending press head supporting bracket 3. The main frame also has a rearwardly extending treadle pivot bracket, 4.

Pivotedly mounted on a pin 5 arranged in the treadle bracket 4 is the main treadle 6 which extends out to the front of the machine and is there provided with an enlarged foot portion 7 arranged conveniently for the operator.

The treadle 6 is provided within the frame

with a roller 8, shown in dotted lines, for 55 engaging an arm 9 of a lever pivoted at 10 in the frame and having an upwardly extending arm 11. This arm 11 carries a roller 12 engaging a cam surface forming a part of an arm 13 extending at substantially 60 right angles to the press head supporting lever 14. This press head supporting lever 14 is fulcrumed at 15 and carries a press head 16 at its outer end. At the opposite end the lever 14 is provided with a counter 65 weight 17. A spring 18 is arranged between the rear end of the lever 14 and the base and tends to open the press. A spring 19 is arranged between the base and the arm 9. Many of the parts just described are shown 70 in dotted lines but this mechanism forms no part of the invention except as it may enter into the combination so that a further showing or further description is not necessary.

Mounted on the buck support 2 is a buck 75 or board 20 of any preferred type capable of coöperation with the head 16.

The foregoing mechanism is substantially the same as that disclosed in the application of Charles L. Braley filed Aug. 14, 1916, 80 Serial Number 114,794 and such mechanism only forms a part of this invention in so far as it enters the combination as before stated.

The feature which forms the specific subject matter of this application is the power mechanism.

This power mechanism comprises a frame 21, Fig. 7, adapted to be applied to the buck support 2 and supporting a power cylinder 90 22. Within the cylinder 22 is a piston 23 secured to a piston rod 24 extending downward and provided with a pressure head comprising a sleeve 25 and a plate portion, 25' horizontally disposed and adapted for 95 engagement with the flat edges 26 of the main treadle which is preferably provided with spaced side portions for the purpose, as shown in Fig. 5. The sleeve 25 is provided with opposed slots each consisting of 100 a straight portion 27 and an abrupt inclined portion 28 communicating with the straight portion. These slots receive rollers 29 mounted on pins 30 secured in two downwardly extending arms 31 projecting 105 from the lower head of the cylinder.

When the piston is in its upper position the rollers are at the lower ends of the slots

28, and the longer dimension of the plate 25' is parallel with the length of the treadle 6. Therefore, the treadle can rise past the plate 25' to the position shown in Fig. 1. 5 When the treadle is down and the piston is moved down the effect of the rollers upon the cam slots 28, 27 is to turn the plate 25' until its longer dimension is cross-wise of the treadle, in which position the ends of 10 said plate lie above the flat edges 26 of the treadle, and in which position pressure of the piston is transmitted to the treadle and therefore applied to the pressing members and the work therebetween.

15 In order to control the motor means above described and to time it properly with the treadle a suitable valve and operating mechanism therefor is provided consisting of a casing 32 properly supported and in 20 which is a supply chamber 33, Fig. 3, communicating with a supply 34 of air or other fluid pressure. This chamber communicates by a port 35 with a chamber 36, said port being controlled by a hand operated 25 valve 37 provided with a stem 38 having a threaded portion 39 engaging a threaded portion of the casing. The stem 38 passes through a stuffing box structure 40 which prevents leakage at this point. This valve 30 is used to regulate the flow of air or other liquid to the cylinder as will appear. Below the chamber 36 the casing 32 is provided with a combined inlet and exhaust chamber 41 which communicates by means of a pipe 42, with the upper end of the cylinder 22 whereby any air or other liquid supplied to the chamber 41 will pass directly to the cylinder and move the piston therein downward. The passage of air or other liquid 40 from the chamber 36 to the chamber 41 is controlled by an inlet valve 42' swiveled, as will appear, upon the end of a stem 43 passing through a stuffing box structure 44 to the outside of the casing 32. A spring 45 surrounds the stem within the casing 32 and tends to seat the valve. The chamber 41 communicates with an exhaust opening 46 controlled by a valve 47 having a gasket 48 and a recess 49 for receiving a head 50 which 50 is held loosely in the recess by a ring 51 threaded or otherwise secured in the valve. The head 50 forms a part of a valve stem 52 which extends out of the casing 32 through a stuffing box structure 53. The 55 valve is held sealed by a spring 54 surrounding the stem 52. The outer end of the stem 52 is threaded into a clevis 55 pivotally connected to a rocker lever 56 which is secured intermediate its ends upon the shaft 57 mounted in the frame and its opposite end is pivotally mounted in a clevis 58 threaded onto the end of the valve stem 43 of the supply or inlet valve already described. The shaft 57 also carries an operating lever 59 60 having one of its two arms pivotally con-

nected to a main treadle operating rod 60 passing through the eye in an ear 61 forming a part of the main treadle. Below this ear the rod 60 is provided with a spring 62 adapted to thrust against an abutment 63 70 secured at the lower end of the rod as shown.

The other arm of the lever 59 is pivotally connected to a release treadle rod 64 extended down and suitably connected to a release treadle 65 pivotally mounted on the 75 base.

The mechanism operates in the following manner.

Assuming that the parts are in the position shown in Fig. 1 and that a garment has 80 been placed upon the buck or board 20, the operator depresses the main treadle 7 causing this treadle through the mechanism already described, to move the head 16 down upon the work. In performing this operation, 85 however, the ear 61 engages the spring 62 and exerts sufficient pressure against this spring so that it shifts the valves in a position to close the exhaust valve and open the inlet with the result that fluid pressure 90 is admitted to the cylinder above the piston therein causing the piston to move downward. The downward movement of the piston causes the head on the end of the piston carrying the plate 25' to be cammed 95 around in a position for the plate to bridge the two edges 26 of the main treadle and to engage these edges and exert a final pressure through the treadle mechanism upon the head. When the parts remain in this 100 position a sufficient length of time, and the operator wishes to release the press the release treadle is depressed causing a shifting of the valves in a manner to close the inlet and open the exhaust, whereupon the spring 105 18 opens the press and the spring 23' moves the piston upward in the cylinder to normal or rest position causing the head at the end of the piston to move the plate out of engagement with the treadle mechanism by the 110 camming action of the walls of the slots in the head.

What we claim is:—

1. In a garment press, a frame, a buck, a press head, means operable by the operator 115 including a lever for closing the press, and power mechanism ineffective upon said lever during the closing stroke and adapted to cause actuation of said lever to exert a final pressure upon the work after the press is 120 closed.

2. In a garment press, a frame, a buck, a press head, means operable by the operator including a lever for closing the press, and power mechanism ineffective upon said lever 125 during the closing stroke and adapted to cause actuation of said lever to exert a final pressure upon the work after the press is closed, said power mechanism being under control of said lever.

3. In a garment press, a frame, a buck, a press head, means operatable by the operator including a lever for closing the press, and fluid actuated power mechanism controlled by said lever and coöperating therewith to exert a final pressure upon the work after the press is closed.
4. In a garment press, a frame, a buck, a press head, means operatable by the operator including a treadle for closing the press, and power mechanism controlled by said treadle and adapted to engage the treadle to exert a final pressure upon the work after the press is closed.
5. In a garment press, a frame, a buck, a press head, means operatable by the operator for closing the press including a treadle suitably pivoted and having a free outer end for manipulation by the operator, power mechanism engaging the treadle near its free outer end for exerting a final pressure upon the work, and means actuated by said treadle for controlling said power mechanism.
6. In a garment press, a frame, a buck, a press head, means operatable by the operator for closing the press including a treadle, and power mechanism under the control of the press closing means and adapted to engage the treadle for exerting a final pressure upon the work.
7. In a garment press, a frame, a buck, a press head, means operatable by the operator for closing the press including a treadle, and power mechanism under the control of the press closing means and adapted to engage the treadle for exerting a final pressure upon the work and comprising a fluid cylinder and piston construction, and suitable valve mechanism therefor controlled by the treadle.
8. In a garment press, a frame, a buck, a press head, a lever operatable by the operator and mounted on the frame, operative connections between the said lever and the press head for closing the same, and power mechanism ineffective upon the said lever during its closing stroke and arranged to cause actuation thereof for exerting a final pressure upon the press head after it has been closed.
9. In a garment press, a frame, a buck, a press head, a member operatable by the operator and mounted on the frame, operative connections between said operatable member and the press head for closing the same, power mechanism ineffective upon said operatable member during its closing stroke and arranged to coöperate therewith for exerting a final pressure upon the press head after it has been closed, and means actuated by said operatable member for automatically controlling said power mechanism.
10. In a garment press, a frame, a buck, a press head, a member operatable by the operator mounted in the frame, operative con-
- nnections between the said operatable member and the press head for closing the same, power mechanism for engaging the said operatable member and for exerting a final pressure upon the press head after it has been closed, and means actuated by said member for automatically controlling the operation of the power means.
11. In a garment press, a frame, a buck, a press head, a lever operatable by the operator and mounted in the frame, operative connections between said lever and the press head for closing the same, power mechanism for engaging said lever and for exerting a final pressure upon the press head after it has been closed, said mechanism comprising a fluid cylinder and piston structure ineffective upon said lever during its closing stroke, and means whereby such structure causes actuation of said lever for exerting a final pressure on the press head after it has been closed.
12. In a garment press, a frame, a buck, a press head, a member operatable by the operator and mounted in the frame, operative connections between said operatable member and the press head for closing the same, power mechanism for engaging said operatable member and for exerting a final pressure upon the press head after it has been closed, said mechanism comprising a fluid cylinder and piston structure ineffective upon said member during the closing stroke, and means actuated by said operatable member for automatically controlling the operation of said power mechanism.
13. In a garment press, a frame, a buck, a press head, a member operatable by the operator mounted in the frame, operative connections between the said operatable member and the press head for closing the same, power mechanism for engaging the said operatable member and for exerting a final pressure upon the press head after it has been closed, said mechanism comprising a fluid cylinder and piston structure, a pressure head actuated by the piston and normally out of the path of the said operatable member, and means for moving said head into the path of the said operatable member upon its final pressing movement.
14. In a garment press, a frame, a buck, a press head, a member operatable by the operator mounted in the frame, operative connections between the said operatable member and the press head for closing the same, power mechanism for engaging the manually operatable member and for exerting a final pressure upon the press head after it has been manually closed, and comprising a fluid cylinder and piston structure, a pressure head actuated by the piston and normally out of the path of the said operatable member, and a cam slot and pin construction for moving said head into the path of

the said operatable member upon its final pressing movement.

15. In a garment press, relatively movable pressing members, an operator-operable member having operative connections with the said pressing members for closing the same, power mechanism for engaging said operator-operable member and for exerting a final pressure between said pressing members after the same have been closed, and comprising a member normally out of the path of the said operator-operable member, and means for moving said member into the path of said operator-operable member upon its final pressing movement.

16. In a garment press, relatively movable pressing members, an operator-operable member having operative connections with the said pressing members for closing the same, power mechanism for engaging said operator-operable member and for exerting a final pressure between said pressing members after the same have been closed and comprising a member normally out of the path of the said operator-operable member, and cam mechanism for moving said member into the path of said operator-operable member upon its final pressing movement.

17. In a garment press, relatively movable pressing members, an operator-operable member having operative connections with the said pressing members for closing the same, power mechanism for engaging said operator-operable member and for exerting a final pressure between said pressing members after the same have been closed and comprising a member normally out of the path of the said operator-operable member, and means actuated by said operator-operable member for moving said member into the path of said operator-operable member upon its final pressing movement.

18. In a garment press, relatively movable pressing members, an operator-operable member having operative connections with the said pressing members for closing the same, power mechanism for engaging said operator-operable member and for exerting a final pressure between said pressing members after the same have been closed and comprising a member normally out of the path of the said operator-operable member, and a cam slot and pin construction for moving said member into the path of said operator-operable member upon its final pressing movement.

19. In a garment press, relatively movable pressing members, an operator-operable member having operative connections with the said pressing members for closing the same, power mechanism for engaging said

operator-operable member and for exerting a final pressure between said pressing members after the same have been closed and comprising a rotatably mounted pressure member normally out of the path of the said operator-operable member, and means for rotating said pressure member into the path of said operator-operable member upon its final pressing movement.

20. In a garment press, relatively movable pressing members, an operator-operable member having operative connections with the said pressing members for closing the same, power mechanism for engaging said operator-operable member and for exerting a final pressure between said pressing members after the same have been closed and comprising a pressure member mounted for rotation upon a vertical axis and normally out of the path of said operator-operable member, and means for rotating said pressure member into the path of said operator-operable member upon its final pressing movement.

21. In a garment press, relatively movable pressing members, an operator-operable member having operative connections with the said pressing members for closing the same, power mechanism for engaging said operator-operable member and for exerting a final pressure between said pressing members after the same have been closed and comprising a rotatably mounted pressing member having a cam slot and being normally out of the path of said operator-operable member, and a relatively fixed pin adapted for co-action with said cam slot, whereby the pressure member is rotated into the path of said operator-operable member upon its final pressure movement.

22. In a garment press, relatively movable pressing members, an operator-operable member having operative connections with said pressing members for closing the same and being provided with spaced extensions, power mechanism for exerting a final pressure between said pressing members after the same have been closed and comprising a pressure member normally occupying a position between said spaced extensions, and means for moving said pressure member into engagement with the extensions of said operator-operable member upon its final pressing movement.

In testimony whereof we affix our signatures.
